[57] CLAIM

The ornamental design for a telephone set, substantially as shown and described.

DESCRIPTION

FIG. 1 is a front, top and right side perspective view of a telephone set showing our new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and

FIG. 7 is a bottom plan view thereof.

The cord in the sundry Figures is shown in abbreviated form for ease of illustration and clarity of presentation.
